DESIGN FOR A COMPACT OR SIMILAR ARTICLE

Charles A. Dunn, Providence, R. I., assignor to Lucien Lelong, Inc., Chicago, Ill., a corporation of Illinois

Application August 2, 1935, Serial No. 57,916

Term of patent 3½ years

To all whom it may concern:

Be it known that I, Charles A. Dunn, a citizen of the United States and a resident of the city of Providence, county of Providence, and State of Rhode Island, have invented a new, original, and ornamental Design for a Compact or Similar Article, of which the following is a specification, reference being had to the accompanying drawing, forming a part thereof.

On the drawing:

Figure 1 is a top plan view of the compact showing my new design, and Figure 2 is a side view thereof.

I claim:

The ornamental design for a compact or similar article, as shown.

CHARLES A. DUNN.
